[57] CLAIM

The ornamental design for a vehicle carrier attachment,
as shown and described.

DESCRIPTION

FIG. 1 is a front elevational view of a vehicle carrier attachment showing my new design, it being understood that the broken lines are for illustrative purposes only;

FIG. 2 is a greatly enlarged rear perspective view thereof;

FIG. 3 is a front elevational view of FIG. 2;

FIG. 4 is a top plan view of FIG. 2;

FIG. 5 is a left side elevational view of FIG. 2;

FIG. 6 is a right side elevational view of FIG. 2; and

FIG. 7 is a bottom plan view of FIG. 2.
